UNITED STATES PATENT OFFICE.

JOHN C. KENNEDY, OF DETROIT, MICHIGAN.

APPARATUS FOR OZONIZING AIR.

SPECIFICATION forming part of Letters Patent No. 430,387, dated June 17, 1890.

Application filed February 26, 1889. Serial No. 301,225. (No model.)

To all whom it may concern:

Be it known that I, JOHN C. KENNEDY, a citizen of the United States, residing at Detroit, in the county of Wayne and State of Michigan, have invented certain new and useful Improvements in Apparatus for Ozonizing Air, of which the following is a specification, reference being had therein to the accompanying drawings.

10 This invention relates to new and useful improvements in apparatus for ozonizing air and for collecting and storing it, and is designed for the production of ozonized air for therapeutic use as used in connection with medical apparatus for compressing, medicating, and administering air, as in a medical apparatus for which I applied for Letters Patent December 13, 1888, Serial No. 293,442; and the invention consists in the peculiar appliances 15 for producing ozonized air, and, further, in the peculiar way of collecting and storing the same for use, all as more fully hereinafter described and shown in the accompanying drawings, in which—

25 Figure 1 is an elevation of my apparatus, and Fig. 2 is a detached section through the ozonizing-electrodes.

A is a machine for the generation of static electricity, such as the well-known Holtz machine.

30 B and B' are the conductors which carry the positive and negative electrodes C and C' of the machine, respectively. Each of these electrodes is provided with a series of points D and D' for the silent discharge of electricity 35 between the electrodes.

E is a vulcanite rubber or other insulating internal housing in which the electrodes are inclosed.

40 F is an air-induction port into the housing, preferably at or near the circumference of the housing.

G is an air-eduction port which communicates with an air-pump H, preferably through 45 one of the conductor-arms B', which is made hollow and is provided with a suitable nipple B'', to which the rubber tube I is attached. The conductor-arm B' is preferably extended 50 inwardly into the housing by means of the insulating-tube J, whereby the eduction-port

is located between the electrodes in or near the center of the housing.

K is another or external insulating-housing inclosing the whole static machine, and this is preferably formed of glass provided with 55 suitable openings for the rubber tube I and the drive-belt L, by means of which the static machine is operated.

M is a suitable motor, preferably a small electric motor, for operating the pump and 60 static machine.

N is a reservoir, into which the ozonized air from the pump is compressed.

O is a connection between the pump and air-reservoir. P is a valve in said connection. 65

Q is an indicator on the air-reservoir.

R is the discharge-pipe from the air-reservoir, and S is a valve controlling the same.

In practice, the parts being arranged and constructed substantially as described, they 70 are intended to operate as follows: The pump and static generator being set in operation, a large portion of the electricity generated will be discharged between the points of the electrodes, and thereby produce the electrical 75 condition resulting in ozonizing the air between the electrodes. This air is confined by the internal housing, which, moreover, is made of insulating material to prevent the dissipation of electricity, so that the air becomes 80 highly ozonized, and in that condition it is withdrawn into the pump. It will be seen that the air passing through the port F into the housing is thoroughly subjected to the influence of the electrical discharge between 85 the electrodes before it can find its exit through the port G, this being the object of the relative arrangement of the induction and eduction ports. From the pump the air is 90 compressed in the reservoir, from which it may be drawn when required. By placing the insulating external housing K over the static machine I utilize all the electricity generated, as it will be clearly seen that any leakage of the machine acts upon the surrounding air, and this very air is then conducted into the internal housing, where it is subjected to a more intense electrical condition. It is well known that electricity 95 escapes from many points during the active 100

- working of any form of Holtz or induction electric machines. If the machine be inclosed in an insulated case or housing, the air within the housing will be more or less ozonized.
- 5 The main object of the invention is to extract the partially-ozonized air from the case or housing that incloses the generating parts of the machine and to pass it through another or supplemental insulated housing in-
- 10 closing the positive and negative points of the discharge ends of the prime conductors, through and between which partially-ozonized air from the case inclosing the generator is made to pass and the process of ozonizing is completed.
- 15 What I claim as my invention is—
1. In a machine for ozonizing air or gas, a generator of electricity, an insulating-housing inclosing the same, a closed tank or reservoir,
- 20 and means, as the pump II, for educting the air from the housing and forcing it under pressure into the reservoir, substantially as described.
2. In an apparatus for ozonizing air or gas,
- 25 a generator of electricity, an insulating-housing inclosing the same and having an inlet and outlet, and means, as the pump II, for causing a current of air or gas to pass into and through said housing, whereby said cur-
- 30 rent of air or gas becomes ozonized by the electricity escaping from said generator, substantially as described.
3. In a machine for ozonizing air or gas, a generator of electricity, an insulating-hous-
- 35 ing inclosing the same and having an inlet and outlet, and means, as the pump II, connected to the outlet, for drawing through said

housing a current of air or gas, substantially as and for the purpose specified.

4. In a machine for ozonizing air or gas, a 40 generator of electricity, an insulating-housing inclosing the same and having an air-inlet, a closed tank or reservoir, and means, as the pump II and pipe I, for educting the air from the housing and forcing it into the reservoir, substantially as described.

5. The combination, in an ozonizing apparatus, of a generator A, an outer casing K, surrounding the same, having openings, as k, for the admission of air, an internal housing containing the ozonizing-electrodes, having a passage F from the outer housing to the interior of the inner housing, a pipe from the interior housing to a pump, and an air-tight reservoir into which the ozonized air is forced, substantially as described.

6. In a machine for ozonizing air, the combination of an electric generator, a pair of ozonizing-electrodes connected thereto, an insulating-housing surrounding said electrodes, 60 a pipe leading from said housing, a pump drawing ozonized air from the housing, and an air-tight reservoir connected with the eduction of the pump, into which said pump forces the ozonized air, substantially as de- 65 scribed.

In testimony whereof I affix my signature, in presence of two witnesses, this 12th day of February, 1889.

JOHN C. KENNEDY.
